UNITED STATES PATENT OFFICE.

DAVID MAYER, OF BROOKLYN, NEW YORK.

DESIGN FOR A SCARF.

SPECIFICATION forming part of Design No. 35,309, dated November 19, 1901.

Application filed September 20, 1901. Serial No. 76,959. Term of patent 3½ years.

To all whom it may concern:

Be it known that I, DAVID MAYER, a citizen of the United States, and a resident of the city of New York, borough of Brooklyn, in the county of Kings and State of New York, have invented and produced a new and original Design for a Scarf, of which the following is a full, clear, and exact description.

Reference is to be had to the accompanying drawing, forming a part of this specification, in which similar characters of reference indicate corresponding parts in the view.

The figure is a front elevation of a scarf, showing my design.

The design in its entirety consists of a body A, having the middle portion of its head B and a portion below the same appearing in relief, as a neck C and a center piece D on the front face of the body A, in a vertical direction and somewhat narrower at the head portion than the head itself, the portion below

the head gradually increasing in width and the lower ends of the neck and center piece merging gradually into the lower portion of the body A, the head B also appearing with 25 a neckband E.

The leading feature of the design consists of the scarf-body A and the center piece D appearing in relief on the front face of the body.

Having thus described my invention, I 30 claim as new and desire to secure by Letters Patent—

The design for a scarf, as herein shown and described.

In testimony whereof I have signed my 35 name to this specification in the presence of two subscribing witnesses.

DAVID MAYER.
